UNITED STATES PATENT OFFICE.

EDWARD B. CADY, OF CHICAGO, ILLINOIS.

CORSET-CLOSURE.

1,295,690.

Specification of Letters Patent.

Patented Feb. 25, 1919.

Application filed May 20, 1916. Serial No. 98,939.

To all whom it may concern:

Be it known that I, EDWARD B. CADY, a citizen of the United States, and a resident of the city of Chicago, county of Cook, and State of Illinois, have invented certain new and useful Improvements in Corset-Closures, of which the following is a specification.

My invention relates to improvements in closures for corsets, and has for its object the provision of an improved construction of this character so laced in position that the edges of the laced opening in the corset may be at all times drawn into close proximity to each other or adjusted to different widths of opening.

A further object of the invention is the provision of such a construction capable of such adjustments of simple construction and efficient in use.

The invention consists in the combinations and arrangements of parts hereinafter described and claimed.

The invention will be best understood by reference to the accompanying drawing forming a part of this specification, and in which,

Figure 1 is a face view of the front portion of a corset equipped with a closure embodying my invention,

Fig. 2 a horizontal section taken on line 2-2 of Fig. 1, and

Fig. 3 a horizontal section taken on line 3-3 of Fig. 1.

The preferred form of construction as illustrated in the drawing comprises an ordinary corset body 4 provided with a gap or opening 5 at the front thereof. A strip 6 is arranged along one edge of gap 5 and is detachably secured to said edge by means of fastenings 7 and 7'. Eyelets 8 are provided in strip 6 and corresponding eyelets 9 are provided in the opposite edge of the opening 5, as indicated. A shield or guard strip 10 is arranged within the corset under the central and upper portions of gap 5 and is adapted to prevent the bulging of the flesh outwardly through said gap 5 when the corset is worn. Adjacent its top, shield 10 is provided with two transversely alining centrally positioned eyelets 11, and adjacent its bottom with four eyelets arranged in transversely alining pairs 12 and 13, said eyelets being also arranged in vertically alining pairs and positioned to transversely aline with corresponding eyelets in the edges of the opening 5. The lacing 14 is passed through the eyelets 8, 9, 11, 12 and 13 as indicated, to serve as a means for adjusting the corset to the body of the wearer as will be readily understood. The upper portions 15 of said lacing are passed under the corresponding edges of the opening 5 to the eyelets 11 as indicated, this arrangement leaving the edges of the corset free to be drawn closely adjacent each other or widely separated as desired. At the bottom of the shield 10 the strand 16 of the lacing is passed over the opening 5 to the corresponding eyelet 8, thence inwardly and transversely through the registering eyelets 12 and outwardly through the corresponding eyelet 9, the portion 17 of said strand then passing over the opening 5 skipping the next lower eyelet 8, passing inwardly through the proper eyelet 8 and being knotted at 18 about the edge of strip 6 to anchor that portion of the lacing while at the same time leave the edges of the opening 5 free to be drawn into close relation with each other or widely separated as desired. The strand 19 of the lacing 14 is passed over the opening 5 skipping the next lower eyelet 9, passed inwardly through the proper eyelet 9 in registration with eyelets 13, thence under the edge of opening 5 to the eyelets 13, outwardly through the corresponding eyelet 8 and over opening 5 inwardly through the next lower eyelet 9 and knotted at 20 about the edge of opening 5. With this arrangement, the corset may be properly and permanently adjusted to the upper portion of the form of the wearer and put on and taken off by releasing the fastenings 7 and 7'. The lower portion of the lacing is left free for adjustment after the corset is put on. The tightening of the lacing will always result in the proper positioning of the shield 10 under the gap 5 without the use of any other connection between said strip and the corset body, thus saving in the material and also in the thickness of the parts at this point. Owing to the peculiar arrangement of the eyelets in the shield and the passing of the lacing therethrough the edges of the opening in the corset may be adjusted closely adjacent each other or widely separated as desired, the shield in the meantime being accurately held in place. The specific arrangement and knotting of the lacing permits of the permanent adjust-

ment of the upper portion to the form of the wearer and the free adjustment of the lower portion thereof at each donning as circumstances may necessitate.

5 While I have illustrated and described the preferred form of construction for carrying my invention into effect, this is capable of variation and modification without departing from the spirit of the invention. I, 10 therefore, do not wish to be limited to the precise details of construction set forth, but desire to avail myself of such variations and modifications as come within the scope of the appended claim.

15 Having described my invention what I claim as new and desire to secure by Letters Patent is:

A corset having an opening therein defined by free vertically extending edges; 20 eyelets in said edges; a shield arranged under said opening and extending from the top to below the waist and provided at the top with two transversely alining eyelets and at its bottom with four eyelets arranged in 25 substantially transversely alining pairs, the transversely alining pairs of eyelets in said shield being positioned to aline transversely with corresponding eyelets in said edges; and a lacing passing through the eyelets in 30 said edges and said shield, said lacing at the top passing under the corresponding edges of said opening in passing through the eyelets in said shield and at the bottom

having one strand passing over said opening and skipping the uppermost pair of eyelets in the bottom of said shield to pass through the eyelet on the other side of said opening registering with the bottom-most pair of said eyelets, thence inwardly through the corresponding eyelet, transversely under the edge of said opening through the corresponding eyelets in said shield, thence outwardly through the corresponding eyelet in the edge of the opening, thence over said opening through the next eyelet on the opposite edge thereof and being knotted about said last mentioned edge, the other strand of said lacing being passed inwardly through the proper eyelet in the edge of said opening registering with the uppermost pair of eyelets of said shield, thence transversely through the eyelets in said shield, outwardly through the corresponding eyelet in the opposite edge of said opening over said opening skipping the next eyelet in the opposite edge thereof, passing inwardly through the eyelet in the edge of the opening and being knotted about said edge, substantially as described.

In testimony whereof I have signed my name to this specification in the presence of two subscribing witnesses.

EDWARD B. CADY.
